UNITED STATES PATENT OFFICE.

COLIN H. McGREGOR, OF DURANGO, COLORADO.

FORM FOR USE IN ERECTING TAPERED CONCRETE CHIMNEYS.

Application filed July 15, 1921. Serial No. 485,053.

To all whom it may concern:

Be it known that I, COLIN H. McGREGOR, a citizen of the United States, residing at Durango, in the county of La Plata and 5 State of Colorado, have invented certain new and useful Improvements in Forms for Use in Erecting Tapered Concrete Chimneys, of which the following is a specification.

10 This invention is a form for use in constructing reinforced concrete columns or smoke stacks which taper toward their upper ends. The object of the invention is to provide a mechanism which may be shifted 15 vertically as the column or stack rises and contracted in diameter so as to conform to the gradually decreasing diameter of the column or stack. The invention also seeks to provide an apparatus in which the pressure 20 of the green concrete or other plastic composition will be effectually resisted and also to provide means for readily moving the apparatus upwardly with respect to the completed portion of the column or stack and 25 supporting it upon the completed portion to receive and permit the pouring of additional cement to form an additional section or layer 30 of the structure. These stated objects and other objects which will incidentally appear 35 in the course of the following description are attained in such an apparatus as is illustrated in the accompanying drawings and the invention resides in certain novel features which will be particularly pointed out in the appended claims.

In the accompanying drawings—

Figure 1 is a side elevation of an apparatus embodying my invention showing the same in the position assumed after one 40 course of the column or tapered structure has been completed and the apparatus has been partly adjusted to permit the erection of the structure to proceed;

Fig. 2 is a sectional view of the apparatus;

Fig. 3 is a top plan view thereof;

Fig. 4 is a detail horizontal section showing the sliding connection between adjacent sections of the form or mold;

Fig. 5 is a detail perspective view of one of the gripper members of the jack.

In carrying out my invention, I employ a plurality of sections, each of which consists of a board or plate of proper dimensions to sustain the pressure to which it is subjected in use. These sections are con-

nected at their side edges by interengaging 60 slideable members whereby relative vertical movement of the sections will be permitted but relative horizontal movement will be prevented. In the drawings, the reference numeral 1 designates sections which are illustrated as being provided with feet 2 whereby they may be anchored to the ground so as to stand firmly while the lowest layer 65 of cement is being poured. These sections 1 have their side edges converging slightly upwardly to conform to the taper which it is desired to impart to the finished stack or other structure and at their side edges they 70 are equipped with track members 3 which are extended outwardly from the sections, as indicated at 4, and then carried away from the edge of the section concentric therewith, as indicated at 5, and terminated in a hook 75 or reentrant flange 6. Between each two sections 1, I provide a section 7 of similar material and the sections 7 have their side edges also slightly converging upwardly. To the section 7, at the side edges thereof, I 80 secure track members 8 which are constructed with overhanging reentrant flanges or hooks 9 adapted to interengage with the hooks 6, as shown clearly in Fig. 4, so that while the sections 7 may slide vertically upon 85 the sections 1, relative horizontal movement or separation of the sections will be prevented. The sections 7 are intended to be raised as the work of construction progresses, and, in order that they may accommodate the decreasing diameter of the column or the structure, they are preferably 90 formed with vertical hinge joints, indicated at 10, whereby they will be permitted to fold slightly. This folding of the section 7 95 will cause a slightly eccentric surface to be produced upon the stack or column, but it will be so slight as not to be noticeable and not to affect the stability of the structure. Moreover, the said sections may be removed 100 and smaller sections substituted therefor as the height of the stack or column increases. It will, of course, be understood that the sections 1 and 7 cooperate with similar sections to constitute a mold within which the 105 concrete is poured and tamped. The sections 1 and 7 are shown as set to produce the exterior surface of the column, while cooperating sections, designated by the numerals 11 and 12, are disposed at the inner 110 sides of the first described sections concentric therewith, as shown clearly in Fig. 3.

The sections 12 are also provided with hinge joints so that they may buckle inwardly as the internal diameter of the column decreases. It will be readily understood that initially all the sections rest at their lower ends upon the ground and they are held in this position against collapse by suitable means which will be presently described. Concrete or other plastic material is poured into the space between the two circular series of sections and is tamped down in the usual manner. After this first layer or course has set, the sections 7 are moved upwardly and caused to engage a second set of sections 13 corresponding to the sections 1 but having their lower ends of the same dimension or extent as the upper ends of the sections 1. As the sections 7 are raised, the engagement of the track members at the adjacent ends of the sections will cause the sections 7 to approach each other in a horizontal plane and thereby contract to a degree corresponding to the desired taper in the chimney. When the diameter of the structure has decreased to such an extent as to make the use of the sections 7 no longer feasible, other sections 7 of similar construction, but of smaller size, are substituted therefor.

In order that the sections 7 may be raised when necessitated by the condition of the work, I provide lifting mechanism consisting primarily of standards 14 secured rigidly to the outer face of an outer section 7 and to the inner face of the inner mating section 12. These standards are connected immediately above the sections by a cross bar or brace 15 and at their upper ends are connected by a bracing head 16. The concrete is reinforced in the usual or any preferred manner by metallic reinforcements embedded therein as the pouring proceeds, and I also provide smooth vertical rods 17 between the mating standards 14 which extend to a considerable height. These vertically disposed rods 17 are so located as to pass through the heads 16 connecting the standards 14 and they, therefore, constitute guides or posts upon which the jacks consisting of the standards 14 and their connections may be mounted to operate when the sections are to be raised. An exteriorly threaded sleeve or jack screw 18 is fitted around the rod 17 and extends through the head 16, a nut or collar 19 being secured to the head and engaged by the jack screw passing therethrough. The lower end of the jack screw is swiveled in a gripper body 20 having seats 21 on its under side in which are fitted grippers or dogs 22 having recesses 23 in their edges to engage the rod 17 between them and these recesses are preferably corrugated, as indicated at 24, to more firmly bind upon the rod. The jack screw has a reduced angular terminal 81 at its upper end upon which is fitted a head 82 provided,

in its edge, with sockets 83 to be engaged by any convenient form of lever. To raise the form sections, the jack screw is rotated, the dogs 22 being locked to the rod 17 so that the turning of the screw through its engagement with the nut or collar 19 will cause the yoke frame 14, 15, 16, to ride upwardly until the member 16 touches the head 82 whereupon the direction of rotation of the screw is reversed, releasing the dogs and causing the screw to ride upwardly upon the rod 17 until the gripper body 20 strikes the nut or collar 19.

Secured to the several standards and extending laterally therefrom are arms 25 which support the rings or annular bands 26, it being noted that these lateral supporting arms and the annular bands are duplicated near the upper and lower ends of the sections. They are also duplicated at the inner side of the sections and upon the outer circumference of the inner band of each pair of bands is a rack 27, a rack 28 being provided upon the inner face of the outer co-operating band, as clearly shown in Fig. 3. Rotatably fitted in the supporting arms 25 between the co-operating annular bands is a shaft 29 equipped with pinions 30 which mesh with the respectively adjacent racks 27 and 28, as shown in Figs. 2 and 3. Each of these annular bands carries upon that peripheral face which it presents to the adjacent form section a wedge or block 31 adapted to bear against a mating block 32 on the section and it will now be readily noted that if the shaft 29 be rotated in the direction indicated by the arrow in Fig. 3, the bands co-operating therewith will be caused to move in opposite directions and the reversely disposed presser blocks or cams carried thereby will be caused to ride over the inclined faces of the blocks 32 on the sections and the sections will be thereby pressed firmly into the desired position and held in that position against the pressure exerted thereon by the concrete. The wedges or blocks carried by the inner sections and the inner annular bands are arranged reversely to those upon the outer sections and the outer bands to permit the inner sections to contract as the form is carried upwardly and in this manner I accommodate both the inner and outer members of the form to the decreasing diameter of the column or other structure.

So far as I am aware, movable or slip forms have not heretofore been employed in the erection of tapered columns or other tapered structures and it has been necessary to employ scaffolding and forms extending the entire height of the chimney and to construct different sets of forms as the work progressed. My invention, however, provides a simple, easily operated and inexpensive apparatus which may be shifted up-

wardly as the structure rises and will eliminate a large number of forms now deemed necessary and result in a vast saving of time and labor so that the cost of erection will be reduced.

Having thus described the invention, what is claimed as new is:

1. An apparatus for the purpose set forth comprising a plurality of sections having 10 slidable engagement at their adjacent edges, means for holding the sections against collapse, and means for raising some of the sections while retaining their engagement with the adjacent sections.

15 2. An apparatus for the purpose set forth comprising a plurality of sections having their side edges converging upwardly, track members secured to the side edges of the several sections and formed with interengaging reentrant flanges whereby relative vertical sliding movement of the sections will be permitted but relative horizontal movement will be prevented, means for preventing collapse of the sections, and means 20 for raising some of the sections while retaining their engagement with the adjoining sections.

3. An apparatus for the purpose set forth comprising a plurality of sections having 30 slidable interlocking engagement at their side edges, said edges converging upwardly, jacks secured to and rising from some of

the sections, and means carried by said jacks to engage a rod rising between said sections whereby to lift the sections to which the 35 jacks are secured while retaining the engagement of said sections with the adjoining sections.

4. In an apparatus for the purpose set forth, the combination of a plurality of sections having their side edges converging upwardly and having interlocking sliding engagement at said edges, means whereby some of the sections may be raised while retaining their engagement with the adjoining 40 sections, and means carried by said raising means for preventing collapse of the sections and permitting them to have slight inward movement as they are raised.

5. In an apparatus for the purpose set forth, the combination of a plurality of sections arranged concentrically and forming inner and outer circles, some of the sections being slidable upon the adjoining section, means for effecting vertical movement of 55 said slidable sections, supporting arms projecting laterally from the last-mentioned means, annular bands carried by said supporting arms, means for moving the adjacent annular bands in opposite directions, 60 and co-operating wedges carried by the bands and the sections respectively.

In testimony whereof I affix my signature.
COLIN H. McGREGOR. [L.s.]
